DESIGN FOR AN ARTICULATED BUS

Knut Henrichsen, Bel-Air, Calif., assignor to
North American Aviation, Inc., Inglewood,
Calif., a corporation of Delaware

Application March 25, 1946, Serial No. 127,945

Term of patent 14 years

(Cl. D14—3)

To all whom it may concern:

Be it known that I, Knut Henrichsen, a citizen of the United States, residing in Bel-Air, in the county of Los Angeles and State of California, have invented a new, original, and ornamental Design for an Articulated Bus, of which the following is a specification, reference being had to the accompanying drawing, forming a part thereof.

Fig. 1 is a perspective view of an articulated bus, showing my new design.

Fig. 2 is a side elevational view of said articulated bus.

Fig. 3 is a rear end elevational view.

Fig. 4 is a top plan view of said articulated bus.

I claim:

The ornamental design for an articulated bus, substantially as shown.

KNUT HENRICHSEN.
